[57] CLAIM

The ornamental design for a combined bottle and closure, as shown and described.

DESCRIPTION

FIG. 1 is a top plan view of a combined bottle and closure embodying our new design;
FIG. 2 is a front elevational view thereof, the rear elevational view being the same in appearance;
FIG. 3 is a right side elevational view thereto, the left side elevational view being the same in appearance;
FIG. 4 is a bottom plan view thereof;
FIG. 5 is a perspective view thereof; and,
FIG. 6 is another perspective view thereof.
